UNITED STATES PATENT OFFICE

GEORGE HOLT FRASER, OF BROOKLYN, NEW YORK

PULVERIZER AND SEPARATOR

Application filed September 12, 1924, Serial No. 737,413. Renewed September 25, 1930.

This invention relates to pulverizers and separators for grinding materials and separating fine from coarse material, and aims to provide certain improvements in such devices.

Pulverizers in which the material is ground between the inner face of a horizontal annular die and the periphery of a roller within the die have heretofore swung or pushed the rollers around the die to generate centrifugal crushing force, and plows or scrapers have been used to throw the material to be crushed on to the inner face of the die in advance of the rolls, the dust formed being removed by an air current rising through the die in a circuitous path to permit large particles to precipitate and fall back into the die and to float the fine particles out to a dust collector or separator arranged in an endless circuit with the pulverizer so that the same air current may be used. The die has usually been stationary, and the rolls have been pushed by or suspended to swing from a revolving spider. The separator has usually been outside of the pulverizer and connected with it by piping, and an outside blower has usually served to generate a considerable air current required for operating such a system.

Pulverizers of the ring roll type have revolved the horizontal ring to hold the material on its inner face, the rolls being carried in non-rotary bearings and pressed toward the ring for crushing the material which latter as discharged has been conveyed to an outside separator to remove the fine dust and return coarser particles to the pulverizer.

My present invention aims to provide improvements especially applicable to pulverizers of the horizontal ring and centrifugal roll type, and aims to provide an improved crusher or pulverizer, and an improved air separator, and to provide an improved combined pulverizer and air separator, and to improve the operation, increase the efficiency, simplify the manipulation, and improve the construction and operation of such devices.

To this end in carrying out the preferred form of my present improvements as applied to a horizontal ring and suspended roller pulverizer I preferably revolve both the rolls

and the ring, the rolls preferably in one direction and the ring in the other, so that the centrifugal force of the rolls may be used as a crushing force and the centrifugal force of the material may be used to keep it on the inner face of the ring and return it to the path of the rolls when it is displaced;

And I preferably revolve the rolls and ring by traction, and at different and variable speeds and provide means for adjusting their respective speeds or for discontinuing drive of either or both, and for utilizing their weight as a traction force for driving them;

And I preferably provide a revolving separating chamber above the ring for receiving the upflowing air and directing it inwardly to the fine outlet, and a revolving deflector therein for receiving the precipitated particles and redirecting them to the crushing elements;

And I preferably provide a revolving chamber encircling endless annular air circuit surrounding the revolving chamber or ring and communicating between the upper fine outlet and a lower current inlet beneath and preferably inwardly of the rolls, and provide dust filtering means across and for intercepting fine material in this circuit;

And I preferably provide filtering means surmounting current means above the revolving chamber or ring, preferably as a revolving fan above the filtering means and within and concentric of the endless current passage, and preferably having radially adjustable blades revolved at variable speed by and driven with the roll carrier for circulating air through this endless circuit in the form of a vortex ring, and preferably I provide supplementary fans for circulating air through the discharge chamber and around the deflector above the rolls in a minor selecting current auxiliary to the main dust current;

And I preferably provide a non-rotative and adjustable feed pipe and a centrifugal discharging feed disc for the fresh material and an annular interceptor for arresting projected feed and dropping it in front of the rolls, and scrapers for this deflector and for

the discharge chamber and for the rock pan below the ring;

5 And I preferably provide a horizontally movable horizontal outer crushing member or ring so that it can radially move or yield relative to its carrier, and provide means for resisting the inner stress or movement of the rolls and for distributing the stress of each roll to another or others as a crushing force 10 inwardly of them and for preventing their undue movement,

15 And I provide various other features of improvement in construction, arrangement, combination and operation, all of which will 20 be more fully hereinafter set forth with reference to the accompanying drawings in which

25 Fig. 1 is a vertical axial section of the preferred adaptation of my invention as a combined suspended roller pulverizer and air separator,

Fig. 2 is a transverse section thereof cut on the planes of the lines 2—2 in Fig. 1,

25 Fig. 3 is a transverse section thereof cut on the planes of the lines 3—3 in Fig. 1

Fig. 4 is a fragmentary vertical axial section similar to Fig. 1 but showing a modification.

30 Referring to Figs. 1, 2 and 3, let A indicate a horizontal ring or die, B the rolls, C the driving mechanism, D the feed inlet, and E the discharge outlet of a machine for pulverizing and separating materials.

35 These parts may be of any suitable construction, arrangement or operation, for pulverizing rock between the inner face of the ring and the outer face of the rolls, for rotating the rolls or revolving the ring, for feeding material to be pulverized into the ring, and for discharging pulverized material. The ring may be disposed in a horizontal plane, and may be movable. One or 40 more rolls may be used and pressed toward the inner crushing face of the ring in any suitable manner to crush the material between the outer crushing face of a roll and the inner crushing face of the ring. The rolls may be planetary and moved by a revolving carrier or spider, and they may be movable with or relatively to it radially of the ring. The axis of the ring may be in a 45 vertical or other plane, and when a plurality of rolls are used they should be eccentric of and disposed about the axis of the ring.

50 According to the preferred form of my invention the ring A revolves to hold material by centrifugal force on its inner crushing face, which is preferably transversely concave or recessed to afford a crushing chamber within it and the ring can yield, gyrate or move radially to adapt itself to the crushing stress, or to cushion shocks, or to meet vibration.

55 According to the preferred form of my in-

vention the rolls are planetary and revolve around the axis of the ring at a different speed than and preferably in reverse direction to the direction of revolution of the ring, and each roll is individually rotatable, as by traction of its preferably convex outer crushing face with the inner face of the ring, each roll being preferably, rotatably and swingingly suspended by a rocking bearing or sleeve F from a revolving carrier or spider G 70 which pulls or pushes the rolls around with sufficient speed to generate the desired centrifugal force as a crushing force to move them radially toward the inner face of the ring, while permitting each to retire under 75 the crushing stress, which stress as to each roll is preferably transmitted to each of the other rolls as a crushing force by a movable and yielding transmitter H, which is preferably a ring intermediate of the sleeves F, 80 suitably engaging each sleeve as by a link or rocker I to participate in the radial movement of each and pressed by a spring or springs J to resist inward radial movement and to press the rolls outwardly to generate 85 or augment their crushing pressure. The transmitter H sustains the inward stress of the rolls and equalizes their crushing pressure by distributing this stress from one to another of them. It is radially and axially 90 movable to adapt itself to the movement and condition of the rolls, and can be adjusted as by the screws K to retire the rolls, to limit their outward movement, or to permit their removal.

95 At one side of the ring I preferably provide a lower current inlet, as L, to admit a separating current under the ring, and an annular wall L to receive material and direct it on to the inner face of the ring. This wall is preferably a pan, tapering or conical and 100 preferably revolves with sufficient speed to centrifugally refeed on to the ring any material passing between or forced off by the rolls, and preferably the ring and pan are 105 mounted one on the other so that they revolve and move together. As shown the pan carries the ring, and has a reversely inclined inner edge to prevent leakage, and serves as 110 a closure for the crushing chamber at its side of the ring.

115 At the opposite side of the ring I preferably provide an upper current outlet, as d, to discharge dust laden current over the ring, and preferably a discharge chamber M, enclosed by an annular wall a, which is preferably conical or tapering from the ring inwardly, and preferably is mounted on and revolves with the ring and participates in its movements. The wall a affords a closure for 120 the crushing chamber at its side of the ring and preferably has a flat or other shaped top wall b and a tapering or reverse neck c terminating in a contracted inner outlet d. The chamber M permits coarse particles to pre- 125

cipitate or centrifugally separate from the fine dust discharging through it, and such particles fall by gravity to the ring or are returned thereto by centrifugal force on the revolving tapering wall *a*, so that only dust goes to the succeeding selecting chamber or the outlet *d*.

To facilitate separation of dust from larger particles in the chamber *M* I prefer to use an annular deflector *e* opposite the neck *c* on which such particles may precipitate and through which they may return to the rolls affording a selecting chamber.

In my endless current passage encircled non-rotary crushing chamber or ring pulverizer, shown in my Patent No. 1,499,516 dated July 1, 1924, I provided fine material intercepting filtering means across the endless current passage, and I provided below such filtering means, and spaced below such non-rotary crushing chamber or ring, a revolving blower connected at its suction side of the egress side of the filtering means for sucking the air from below and inwardly of the filtering means to clean dust from the air and to return the cleaned air under the lower inlet of my said filter crossed non-rotary chamber encircling endless current passage pulverizer, but according to one feature of my present invention I provide revolving fan blades above the filtering means, and extending outwardly in the endless passage above the crushing chamber or ring, for sucking dust laden air directly from the crushing chamber or ring, and blasting it toward the filtering means, to increase separation and filtration efficiency.

According to the preferred form of my invention I provide an air separator surrounding and enclosing a revolving crushing chamber pulverizer and its crushing elements and crushing chamber, for separating the dust as it is made and within instead of without the device, which serves as an enclosing casing for the apparatus, and makes a single combined unit of these elements, and preferably I also provide a dust collector for cleaning the air within and enclosed by the air separator and around and enclosing the crushing chamber, and elements, to receive the air separating the dust, and preferably I also provide across the revolving chamber encircling endless current passage non-rotary filtering means to intercept fine material in the air and to filter and clean it and restore cleaned air to within the crushing chamber.

In its preferred form the air separator *N* encloses the pulverizing parts and the dust collector *O* and air filter or cleaner *P*, and the dust collector surrounds the pulverizing parts and the filter, and the filter is below such parts and surrounds the driving chamber *Q* for the driving mechanism for revolving them, and these parts are disposed concentrically and in spaced relation. Preferably the air separa-

tor is a centrifugal or cyclone separator and has a casing comprising a flat top wall *f*, a downwardly inclined deflecting wall *g*, a cylindrical side wall *h*, and a tapering bottom wall *i* terminating in a dust outlet *j*, which walls enclose a chamber *k* in which the current generating and whirling means are disposed, and which encloses the pulverizer, dust collector or filter and driving chamber, which parts partition its interior to afford an endless current passage up through the lower opening or inlet *l* in to the pulverizing chamber and through the selecting chamber *M* and outlet *d* of the pulverizer and the upper opening or fan way *m* out to the chamber and down through this to the inward opening *n* of the dust collector and through the filter to the inlet *l*, through which the air can circulate through and around the crushing chamber and through the device surrounding it.

Preferably, according to another feature of my invention, revolving crushing chamber superposed and non-rotary filtering means surmounting, concentric current causing and intensity varying means, preferably as a revolving blower or fan *R* is provided between the flat top *b* of the pulverizing chamber and the flat top *f* of the air separator and has blades *O'* encircled by and with inclined outer edges coinciding with the inclined deflecting wall *g*, so that when it revolves it will force the air against this wall which will deflect it downwardly through the chamber *k* and cause it to circulate through the endless circuit. Preferably the air is centrifugally whirled in the chamber *k*, as by blades *o* mounted on and revolving with the wall *a* of the revolving chamber *M*, to generate sufficient centrifugal force to cause dust in the current of air descending through the chamber *k* to move outwardly against its outer wall and precipitate down the latter in to its dust cone *i*, and this whirling of the air is arrested by radial checks or vanes *p* which are spaced sufficiently below the whirlers *o* to afford a centrifugal separating chamber or space above the checks, and opposite this space I prefer to locate the annular inlet *n* for the dust collector, so that it will draw relatively clean air from within the downwardly whirling current. Air entering the inlet *n* descends in the vertical chamber *q* of the dust collector, past whirl checking vanes *r* therein, and enters and then flows inwardly through the filter *P*, which is preferably non-rotary, and below and at the egress side of the fan *R*, and across the endless current passage, and is preferably constructed with two annular rows of baffles or troughs *s* in staggered relation and arranged one inwardly of another so that air may flow between their spaced edges, and as it passes these will form dead air spaces in front of the baffles in which floating particles may precipitate and be intercepted, and through which they may be

110

115

120

conducted below the zone of such current without molestation thereby. Dust precipitating in the dust collector and descending from the filter will be received in the lower bottom cone *t* of the dust collector and conducted to its fine outlet *u*.

The conical bottom wall *v* of the filter isolates this from the dust collector except by communication through the filter medium or troughs, and preferably has a bottom outlet *w* controlled by a weighted automatic dumping or discharging valve *y* which in case of accumulation within the filter serves to open and release such accumulation and discharge it into the cone *t* of the dust collector.

According to the preferred form of my invention the blower *R* is above and concentric of the revolving crushing chamber or ring, and of the non-rotary filtering means, and is adjustable, and revoluble at variable speed, to vary the intensity of the separating current, and preferably is revolved with the revolving carrier for the rolls and is preferably carried thereby, so that the blower action will coincide with the speed at which the rolls are whirled, and vary with variations thereof, and its blades are radially adjustable relatively to the inclined deflecting wall *g* encircling them, to vary the blower action. This may be provided for in any suitable manner, and the blades may be of any suitable construction, but according to the preferred form of my invention each blade *O'* is mounted near its lower edge on the side of a spaced spoke *P'* and attached to the side of its spoke by a fastener *Q'* engaging one or another of a plurality of holes *R'* through the side of the spoke, the number and position of the holes being determined by the desired adjustments, and as shown sufficing for the outermost adjustment of the blades shown in full lines in Fig. 1 when the fastener engages the outermost hole *R'* and for the innermost position of the blades shown in dotted lines in Fig. 1 when the fastener engages the innermost hole *R'*. Making the adjustable blades *O'* upstanding above the lower spaced spokes *P'* affords a high air passage or chamber *S'* above the spokes and utilizes the height of the blades above the spokes as a high air chamber through which the air rising through the spaces between the spokes can flow to the blades and also affords a high clear space into which the inner edges of the blades may pass as the blades are adjusted from the deflecting wall, and in which the valve operating rod *l2* may move vertically without interfering with the blades. Preferably the spokes are mounted on the spider *G*, which is preferably provided with a tubular upwardly extending neck or part *S* which carries the blower.

Material may be fed into the ring in a suitable manner but according to the preferred form of my invention I provide a revolving centrifugal feeder or disc *T*, on or prefer-

ably part of the carrier *G*, and I provide a non-rotary feed pipe *U* the lower end of which opens above and opposite the center of the disc *T*, and which rises concentrically of the tube *S* and is adjustably mounted on the top *f* of the air separator so that it can be adjusted vertically to permit more or less material descending from the hopper *D* to flow on to the feed disc *T*. The lower part of the tube *S* is open at suitable intervals over the disc *T* to afford outlets *j2* between its legs *h2* for material flowing on to it, so that this material can be projected centrifugally over the rolls *B* above which the disc is suitably disposed.

My invention preferably provides for intercepting this centrifugally fed material and permitting it to slowly fall within the ring and I preferably provide an annular deflecting interceptor, spreader or distributor *V* disposed in the path of the material and inwardly of the material and inwardly of the inner diameter of the ring and intermediate of the upward current passage so that it partitions the upward current and permits it to drop into the ring just above the path of the rolls so that they may act on it before it has passed below them, and any dust contained in it may be lifted by the rising current inwardly and outwardly of the annular interceptor. The interceptor is preferably mounted on and revolves with the casing *a*.

My invention preferably provides scrapers *z* for scraping off any material which may adhere to or accumulate on the inner wall *a*, the interceptor *V*, or the feeding wall or pan *L*, and these scrapers are preferably mounted on and revolve with the carrier *G*.

My invention preferably also provides for availing of the whirling carrier fans *z* above the feed disc *T*, which are revolved with or by the carrier *G* and serve to circulate air around the deflector *e* in the chamber *M*. Their ingress communicates with the annular bottom outlet of this deflector and they draw the minor current of air through this to facilitate descent of larger dust settling in it and return such dust to the chamber *M*, causing a supplementary current up through this chamber and down above the deflector *e* to supplement the main current and relieve it of the work of circulating this minor selecting current.

The parts may be driven from above or below, or according to any manner suited to the drive desired for either or both, but my invention preferably provides improved means for driving them, and in its preferred form drives them tractively and at different and variable and relatively adjustable speeds. Preferably the ring is carried by a member *W* having a lower traction face driven by a wheel or roller *X* having an edge traction face, and the rolls are driven by a member *Y* having an upper traction face tractively driven by

a wheel or roller Z having an edge traction face, and each of these rollers is adjustable axially to vary the speed of the parts it drives.

As shown the roller X is carried by a tubular shaft a' , revolved by a drive pulley b' , and surrounding a shaft c' which carries the rollers Z, which shafts are keyed or feathered together and to their pulley b' by a pin d' and slot e' or in any other suitable manner so that they will revolve together or can be relatively adjusted axially. Any means may be used for adjusting these shafts, as for example the adjusting levers f' and g' shown. The member W preferably has a track of large diameter so that the ring may be driven at a relatively low speed, and the member Y a track of small diameter so that the rolls may be driven at relatively high speed. Preferably the rollers are the same diameter and the tracks are spaced so that the roller Z may be withdrawn beyond the outer edge before reaching the inner edge of the track of the member W, so that driving of the rolls may be stopped while driving of the ring is continued. The track on the ring preferably is narrow enough to permit of withdrawal of the roll X outwardly so when it is desired the ring will be stationary. For starting or stopping the apparatus without disturbing the rollers I prefer to use a clutch h' on the hub of the pulley b' or any usual or suitable means.

I prefer to movably and removably and yieldingly mount the ring A on the member W and provide a separable driving connection between them, and preferably mount the pan L slidably on the member W and provide inter-engaging provisions on each for causing them to revolve together, and yielding means for positioning them radially of one another.

As shown the member W is provided with notches i' and the pan L with lugs j' entering these notches for causing the parts to revolve together, and springs k' are provided between these parts for cushioning tendency to radial relative movement thereof and normally positioning them concentrically while yieldingly cushioning radial shock.

Preferably the revolving ring A is bolted on top of the pan L, which latter carries the ring and has an under seating face $m2$ resting on and movably supported by an upper sustaining face $n2$ on the carrier W, which thus vertically sustains the ring and pan while permitting their radial movement horizontally in the direction of the crushing stress.

In its preferred form my invention provides filtering means across a revolving crushing chamber or ring encircling endless current passage, and preferably uses non-rotary filtering means across such passage, and includes endless passage encircling

motion or rotation permitting means between the filtering means and the revolving crushing chamber or ring, which may be provided for in any desired manner, but preferably, as shown in Fig. 1, I construct the carrier W with an under bearing face $o2$ which rotatably bears on an upper bearing face $p2$ formed on the upper edge of the gear case Q, which faces afford a vortexical ring encircled movement or revolution permitting joint $q2$ encircled by the endless current passage, permitting the ring to move or revolve in such encircling passage and relatively to the filtering means across such passage.

I prefer to form a member W with a tubular hub, and the carrier G, with a tubular extension l' traversing this hub and having a ball bearing m' which preferably sustains the weight of the carrier and its parts on the member W so that the weight of both will act against the roller X as a traction force, and this roller will sustain this weight and transmit it through the roller Z to the member Y, which will be keyed or otherwise connected to rotate with the carrier, and is preferably sustained by a ball bearing n' on the driving case Q. The pipe l' preferably extends through the member Y and the case Q and has an open lower end affording an inlet l within the filter P for return of filtered air, and at its upper part under the feed disc T and above the pan L it has openings o' for passage of the filtered air into the pulverizing chamber opposite the spaces between the rolls B, the parts being disposed to cause this air to enter and swing downwardly and outwardly across the pan and up the inner face of the ring between the rolls as it rises to the settling chamber M.

To balance the weight of the parts the idling rollers X' and Z' are spaced diametrically opposite the driving rollers or at equidistant points around the axis of the traction rings, and these and the driving rollers are enclosed in the gear case Q to exclude dust and isolate the tractional faces and the anti-frictional bearings for their members from the filter chamber which surrounds and encloses them, and the bearings for the shafts and for the rollers are preferably tubular and enclosed where they traverse the dust collector and air separator passages.

My invention provides for automatically varying the flow or supply of feed to the crushing chamber to regulate such supply as the quantity of material in the chamber to be crushed varies, with the object of maintaining a substantially uniform charge or depth of such material on the inner face of the crushing ring and of preventing clogging or choking of the crushing chamber.

This may be variously accomplished, but

- preferably I provide for automatically varying the discharge from the adjustable feed pipe U and the feed disc T by mounting a vertically movable regulating gate or valve 5 s' around the feed pipe U so that it surrounds this and the central part of the disc T and acts as a dam to regulate flow of material from the pipe and across the disc to the discharge edge thereof. The valve s' is preferably loosely mounted in the tubular neck S of the carrier G and revolves therewith and is movable downwardly therein to more or less close the outlets therefrom above the disc T. It may be moved in any suitable manner, but 10 15 20 25 30 35 40 45 50 55 60 65 70 75 80 85 90 95 100 105 110 115 120 125
- I prefer to automatically operate it from the crushing rolls so that as these are moved in by accumulation of material on the inner face of the ring A they will cause or permit the valve to close to reduce ingress of fresh feed, and as they move out with diminution of material on the inner face of the ring they will cause the valve to open to increase supply of fresh feed. I prefer to sustain the valve s' loosely on the inner ends of levers t' at one side of their fulcrum, and to operate the other ends of these levers by the movement of the roll bearings F, preferably by connecting the levers with the equalizing ring H so that as this rises with the inward movement of any roll it will lift the outer end of the lever t' opposite that roll to permit descent of the valve s' by gravity or other force in case all of the levers t' are correspondingly tilted by a uniform lifting of the ring H by simultaneous inward movement of all of the rolls B. The ring H may float radially intermediate of the rolls to equalize stress and pressure between them, and in so doing slides on the outer ends of the levers t', but it also rises when all of the rolls are pressed in and lowers when all of the rolls move out, and the levers t' follow such lifting and lowering movements of the ring H so that all of the levers move in such case and reversely move or permit movement of the valve s'. Springs u' cause the levers t' to follow the ring H and lift the valve s' when the ring H lowers with outward movement of the rolls, so that then the valve permits ingress of more fresh feed. Springs v' preferably force the valve down when the levers t' permit its descent to reduce or terminate fresh feed, the adjusted flow of which through the pipe U is thus subjected to this additional automatic regulation for varying its discharge into the crushing chamber. Preferably also I provide means for varying or regulating the supply of material by utilizing variations in the current in the ingress and egress sides of the crushing chamber and preferably in both sides. This may be accomplished in any suitable manner, but according to the preferred form of my invention I provide a diaphragm T' between the suction chamber U' communicating with the outlet d and a pressure chamber V' communi-

cating with the crushing chamber just above the inlet openings o', so that back pressure in the crushing chamber tends to lower the diaphragm, or excessive suction within the fan R tends to lower the diaphragm, either or both of which conditions would arise if the crushing chamber became so full of material as to unduly resist current flow through it, in which case the diaphragm will fall and through the levers w' tilt the levers t' to permit the regulating valve s' to descend, and will vary its vertical position with fluctuations in the conditions above and below the diaphragm T' and thus automatically vary feed with variations in current due to variations in the space through which it is permitted to flow caused by accumulation of material in this space.

A passage l2 or a plurality of apertures y' through the tubular part S of the carrier G affords communication between the chamber U' and the ingress side of the fan way m just above the outlet d.

My invention preferably also provides for shutting off feed in case of accident or abnormal conditions, and in its preferred form provides a vertically movable operation controlling automatically operated valve or feed shutoff gate Y' which preferably surrounds the feed pipe U and is preferably carried by a valve operating means or rod l2, and preferably normally stands with its lower edge above the lower end of the feed pipe, and extends through and above the neck S of the carriers G, and is operated by one or more forked levers z', which are tilted by the bearings F when these move excessively to shut the gate Y' down and stop all feed.

As shown if a roll should break and permit its bearing F to fly outwardly the toe a2 of the bearing would tilt the head b2 and cause its lever z' to throw the shutoff gate down, or should uncrushed iron jam a roll inwardly excessively the bearing would tilt until its lower nose c2 would tilt the lever d2 and cause this to tilt the lever b2 to operate the forked lever and throw the shutoff gate down, thus preventing the clogging of the crushing chamber in case of such an accident.

My invention also provides an automatic throwoff or safety means for stopping drive in case of accident, which in its preferred form comprises safety means W', shown as a bell crank e2, sustaining through the valve rod l2 the shut-off gate Y', and tilted by the descent of the shutoff gate Y' and connected to a lever f2 to tilt it and through its connecting link g2 to operate the levers f' and g' to throw the rollers X and Z out of engagement with the wheels W, and Y, or otherwise disconnect driving, thus stopping revolution of these to discontinue operation until the trouble can be investigated and remedied.

Preferably I provide cushioning springs h2 between the bearings and carrier for pois-

ing each bearing and cushioning its swinging movements and arresting these without undue shock to the carrier in case of excess movement, and I normally sustain the shutoff gate open by a weight $i2$ on lever $e2$, which when tilted by descent of the gate permits it to remain closed until it is manually restored.

10 The wheels W and Y , through the engagement of their opposite spaced annular traction faces at diametrically opposite sides with the edge traction faces of the rollers X and Z respectively, serve to balance these as to much of both their radial stress and their 15 driving stress, and correspondingly relieve the stress of their outer rocking bearing p' and inner vertically sliding bearing q' .

15 The wheel Y is movably mounted on its anti-friction bearing n' so that it can oscillate thereon to compensate for or adapt itself to variations in the rollers, and it is keyed or feathered to the tubular hub l' so that the latter can revolve with it and be moved or removed axially relatively to it, the spider G 20 and this hub being preferably formed of one integral casting of which the tubular fan carrying top extension S is preferably also an integral part. This casting is preferably movably and removably mounted on the 25 wheel W , and rotatively sustained therefrom by the anti-friction bearing m' .

25 The fans z carried by the spider preferably extend from near the bottom of the crushing chamber to near the top of the separating chamber M , so that they will suck air through the lower central inlets o' as well as from the feed inlet around the feed disc T , and from the return inlet under the deflector e beneath the selecting chamber K , and will 30 blow this air upwardly and cause it to whirl in the precipitation chamber to centrifugally throw out and return large particles as well as to supplement the effect of the exhaust fan R . The scrapers x are preferably mounted 35 on edges of the fan z to scrape the pan L , the interceptor V , and wall a , in case material accumulates on any of these sufficiently to exceed the clearance between them and the scrapers.

40 In operation, when the parts are disposed about a vertical axis as in the preferred construction, material will be fed by gravity through the feed pipe U from which its escape will be controlled by the adjustment of 45 the end of this pipe toward or from the feed disc T to regulate the speed of feed. The disc will centrifugally project the material in a dust cloud or film over the top of the rolls and against the interceptor V , from 50 which it will fall just inwardly of the inner edge of the ring and into the path of the rolls, so that which is not engaged by them will descend through the ring and into the refeeding pan L , by which it will be centrifugally 55 fed on to the inner face of the ring. In en-

tering and falling the feed will traverse the rising air current and dust contained in the material will be lifted inwardly and outwardly of the interceptor V and into the precipitation chamber M , where the air will be 60 whirled by the fan z and large particles centrifugally extracted so that they may fall back into the ring, while finer dust will be carried over the deflector e and into the selecting chamber K , where the current induced by the blower z will return under the deflector e and the main current will reverse 65

70 and rise through the blower R . In this reversal of current any large particles may precipitate and return for further grinding 75 and only fine dust will rise to the blower R . The latter will drive the dust laden current into the air separator N in which it will be whirled by vanes o as it descends so that most of the coarse dust will be separated by 80 being centrifugally carried against the wall of the air separator down which it can fall to the dust outlet j . Thus the air will be freed of all dust except that which is too fine to be thus centrifugally separated, and 85 this will float inwardly through the inlet n to the dust collector O , so rotation will be arrested and it will descend to the filter P which will clean it by intercepting fine dust 90 remaining in it, so that this may precipitate 95 and escape through the fine outlet u . The cleaned air passing the filter will rise through the bottom inlet l and be discharged inwardly of and between the rolls into the 100 crushing chamber so as to sweep across the annular concave in the bottom of the pan L and up the concave inner face of the ring and rise past the interceptor V into the chamber M and return through the selecting chamber K again to the blower R , the blades of which 105 will be adjusted to produce the desired separating current, and the speed of which will be varied to vary the intensity of the separating current to vary the fineness of separation.

110 The ring will be driven in one direction at a speed which will be varied to give the best results by adjusting its roller X radially of the wheel W , and the spider will be revolved in the other direction at a speed which will be varied to give desired centrifugal force as the crushing pressure for the rolls, or the desired speed for the feed disc T or for the blower R and the complementary fans z . Inward movement of the rolls will be resisted by the equalizer H , which will 115 transmit the inward stress of one roll to another or others, and will swing or move intermediate of their bearings to equalize the stress of each and yieldingly resist excessive movement of any and to cushion shock and vibration thereof. The springs J will yieldingly sustain the transmitter and provide a 120 crushing pressure acting to hold the rolls outwardly to resist a crushing force from the inner face of the ring. The ring will move 125 130

to adapt itself to shocks and vibration, and the springs k' will yieldingly resist and cushion such movement.

- 5 The top f and annular inclined deflecting wall g of the air separator are separable, so that these and the hopper D can be removed to give access to the other parts. The top b with its neck c and the deflector e are removable for access to the parts below them.
- 10 The wall a is separable so that it and the deflector V can be removed to permit access to or removal of the spider and its separably hinged rolls, which may be lifted together or separably from the ring. Retiring the rolls and disconnecting the ring from the pan L permits removal or replacement of the ring. The ring and its pan may be lifted from its driving wheel W after the spider and rolls have been removed. The lower parts of the 15 air separator and dust collector separably depend from the driving chamber Q, which serves as the base or main frame of the apparatus and removably sustains all parts including the filter.
- 20 25 It will be seen that my invention provides improvements which can be variously and advantageously availed of, in whole or in part, and it will be understood that the invention is not limited to the particular details 30 of construction, operation, arrangement, or combination, set forth as constituting its preferred form, since it can be variously and advantageously availed of in whole or in part according to such modifications as circumstances or the judgment of those skilled 35 in the art may dictate without departing from the spirit of the invention.

One such modification is illustrated in Fig. 4, in which the driving mechanism C is above, and the ring A and the rolls B are swingingly suspended from it together with a single air separator N' which encloses the revolving parts. In this construction the ring is mounted in a revolving pan casting 40 L' which has an upwardly extending tubular neck l' carried by an overhead traction wheel W'. The feed pipe U descends through this neck and discharges on to the distributing disc T which is a cast part of the pan L', 45 which is cast with return air openings o' and the air return inlet l communicating with the lower cone i of the air separator. The spider G' here shown has a tubular neck S' by which it is suspended from its overhead 50 traction wheel Y', which is revolved in one direction by its traction roller Z while the wheel W' carrying the ring A is revolved in the reverse direction by its traction roller X. The blower R is mounted on and revolves 55 with the neck S', and the chamber M has a cylindrical casing r' which revolves with the ring and inclined or spiral scrapers x' mounted on the fan z are used to return material 60 to the ring. In this construction, non-rotary 65 filter troughs s , across the revolving crushing

chamber and ring encircling endless current passage, are spaced from the pan L' sufficiently to afford a motion and revolution permitting joint between this pan and these troughs.

While for more fully illustrating the applicability of my improvements claimed herein I have shown them in Fig. 4 as used in connection with my movably suspended die carrier L' and movably suspended spider carrier S', movably mounted above the die 75 and rolls, and my overhead drive for revolving the suspended elements, and my clearance joint between the die and the dust interceptor P below it, these features of improvement are claimed in my co-pending application 80 filed September 1, 1931, Serial No. 560,589.

What I claim is:

1. In combination, an annular crushing die disposed in an approximately horizontal plane and having an annular crushing face, 85 a crushing roll having a peripheral crushing face acting toward said annular face to crush material between said faces, means for revolving said die, means for supplying material to be crushed to said parts, means for withdrawing fine material from said parts comprising an upwardly extending revolving casing affording a chamber above and surrounding said annular crushing face, and means for subjecting such material to centrifugal action within said chamber to centrifugally separate therein and return to said face coarser particles.

2. In combination, an annular die disposed in an approximately horizontal plane and 100 having an annular crushing face, a crushing roll having a peripheral crushing face acting toward said face to crush material between said faces, means for revolving one of said parts, means for supplying material to be crushed to said parts, means for withdrawing fine material from said parts comprising an upwardly extending revolving casing affording a chamber above and surrounding said annular face, and fan blades revolving about 105 the axis of said die and in said chamber for revolving such material around it to centrifugally separate fine from coarser material 110 therein.

3. In combination, an annular die disposed in an approximately horizontal plane and having an annular crushing face, a crushing roll having a peripheral crushing face acting toward said face to crush material between said faces, means for revolving one of said parts, means for supplying material to be crushed to said parts, and means for withdrawing fine material from said parts comprising a revolving casing above said die 115 affording an upwardly extending outlet 120 chamber communicating with said annular face and in which such material may revolve with said casing to centrifugally separate coarse from fine particles thereof.

4. In combination, an annular crushing die 130

disposed in an approximately horizontal plane and having an internal crushing face; a crushing roll having a peripheral crushing face acting toward said face to crush material between said faces, means for revolving one of said parts, means for supplying material to be crushed to said parts, and means for withdrawing fine material from said parts comprising a revolving casing above and surrounding said annular face, and converging in its upward extension thereabove, affording an upwardly contracting exhaust chamber down the tapering wall of which coarse material may return to said annular face.

5. In combination, a revolving die having an annular crushing face, a crushing roll having a peripheral crushing face acting toward said face to crush material between said faces, means for revolving said die, means for supplying material to be crushed to said parts, and means for withdrawing fine material from said parts comprising a casing revolving with said die and affording 20 an upwardly extending outlet chamber in which coarse material may separate and return to said annular face.

6. In combination, an annular die revolving about an approximately vertical axis 30 and having an annular vertically extending crushing face, a revoluble and rotating crushing roll rotating about said vertical axis and having a peripheral crushing face acting toward said face to crush material between said faces, means for revolving said die, means for supplying material to be crushed to said parts, and means for discharging fine material from said parts comprising means for causing a current of air to flow up through 40 said revolving die and within said annular faces to float fine material from said parts.

7. In combination, an annular die revolving about an approximately vertical axis and having an internal crushing face, a crushing roll within and eccentric of said die and having a peripheral crushing face acting toward said face to crush material between said faces, means for revolving one of said parts, means for supplying material to be crushed 50 to said parts, means affording an endless current passage up through and out around said revolving die, and means for causing a current to transverse said passage to float fine material from said parts.

55. 8. In combination, an annular die revolving in an approximately horizontal plane and having an annular crushing face, a crushing roll having a peripheral crushing face acting toward said face to crush material between said faces, means for revolving said die, means for supplying suitable material to be crushed to said parts, means surrounding and enclosing said parts affording an endless current passage through and below 60 and around said revolving die, and means

for causing a current to flow through said passage to float fine material from said parts.

9. In combination, a die revolving about an approximately vertical axis and having an internal crushing face, a roll within and eccentric of said die and having a peripheral crushing face acting toward said face to crush material between said faces, means for revolving said die, means for supplying material to be crushed to said parts, revolving chamber means above and surrounding said internal face affording an upwardly extending discharge chamber for fine material communicating with the space within said die and having an upper outlet, and means for causing fine material to rise from said die through said chamber and to said outlet.

10. In combination, a die disposed about an approximately vertical axis and having an annular crushing face, a plurality of rotatable crushing rolls each having a peripheral crushing face acting toward said face to crush material between said faces, means for revolving said rolls comprising a revolving feeder concentric of said die and above 85 said rolls for centrifugally projecting the material to be crushed toward the inner face of said die, and means for supplying such material to be crushed to said feeder comprising a non-rotary pipe having an open 90 lower end opposite and concentric of said feeder and adjustable to vary such supply.

11. In combination, a die having an annular crushing face disposed about an approximately vertical axis, a plurality of rotatable and revoluble crushing rolls within and concentric with said die and each having a peripheral crushing face acting toward said face to crush material between said faces, a revolving member for revolving said rolls, means for revolving said member, means for supplying material to be crushed to said parts, means affording an exhaust chamber for fine material above and surrounding said parts and communicating with the interior of said die and having above said chamber an inwardly extending top wall affording a fan-way and an inner upper outlet, and fan blades above said die and above said top wall and mounted on and revolving with said 105 revolving member and disposed above said outlet for causing a current of air to flow upwardly through said chamber to float fine material therefrom.

12. In combination, a revolving crushing die having an annular crushing face disposed about an approximately vertical axis, a plurality of rotatable and revoluble crushing rolls within and concentric with said die and each having a peripheral crushing face 110 acting horizontally toward said face to crush material between said faces, a tubular member revolving about said axis for rotating said rolls and having inwardly of said annular face a lower part affording communica- 115

tion with said die, means affording a chamber communicating with said die and having an upper outlet opening above the latter, means affording an endless passage communicating between said outlet opening and under and up through and around said die, and means in said endless passage for causing a current to flow up through said outlet, sweep through said die, rise through said 10 chamber and return without said die.

13. In combination, a die having an annular crushing face disposed about a vertical axis, a plurality of crushing rolls with and concentric with said die and each having a 15 peripheral crushing face acting toward said face to crush material between said faces, means for revolving one of said parts, means for supplying material to be crushed to said parts, means within said die affording a 20 lower inlet for air to said die, means affording a discharge chamber above and communicating with said die and having an inner upper outlet, means affording an annular partition in said chamber spaced around said 25 outlet and having an outer edge spaced from the wall of said chamber and around which air may flow to said outlet and having an inner grit outlet, means affording an endless current passage through said die and said 30 chamber and inner outlet and around said die and through said lower inlet, means for causing a current to traverse said endless passage to float fine material from said die, and means for causing a supplemental current in 35 said chamber to flow through said chamber and around said partition and through said inner grit outlet to select coarse material from said first current and return such selected material to said die.

40 14. In combination, a die having an annular crushing face disposed about an approximately vertical axis, a crushing roll having a peripheral crushing face acting toward said face to crush material between said faces, 45 means for revolving one of said parts, means for supplying material to be crushed to said parts, means affording a chamber above and surrounding said annular face and communicating through and having an inwardly extending upper top wall and an inner outlet 50 concentric of said annular face, means enclosing said inner outlet comprising a wall spaced from and above said upper wall and affording a fan way between said walls and an outlet 55 from said inner outlet, and a tapering wall opposite and surrounding said fan way and affording an inclined outlet therefrom and above and surrounding said chamber, and an annular discharge passage communicating 60 with said tapering wall, and means for causing a current to rise through said chamber comprising fan blades above said inwardly extending upper wall and revolving about said axis and within said fan way to draw air through said outlet and project it against

said tapering wall to deflect it in to said passage for floating fine material from said die.

15. In combination, a revolving die having an annular crushing face disposed about an approximately vertical axis, a crushing roll 70 having a peripheral crushing face acting toward said face to crush material between said faces, means for revolving one of said parts, means for supplying material to be crushed to said parts, means above said die affording an outlet chamber communicating with said die and having an upper current outlet, means communicating below said die and affording a lower current inlet within 75 said die, means enclosing said parts comprising a casing surrounding and in spaced relation to said parts affording an air separating chamber in communication with said upper outlet and said lower inlet and affording an endless current passage through and around 80 and surrounding said die, and means for causing a current to flow upwardly through said revolving die, through said passage and to return below said die and through said inlet. 85

16. In combination, a revolving crushing die having an annular crushing face disposed about an approximately vertical axis, a crushing roll having a peripheral crushing face acting toward said face to crush material between said faces, means for revolving one of said parts, means for supplying material to said parts, means affording a chamber above and communicating with said annular face and having an upper current outlet, means communicating below said die and affording a current inlet within said die, means comprising a casing surrounding and in spaced relation to said parts and affording an annular current passage around said parts and an air separating chamber communicating between said upper outlet and said lower inlet, means for causing a current to flow up through said die to float fine material therefrom and through said upper outlet and down through said passage and return through said lower inlet, and means for revolving such current in said passage to centrifugally separate particles floating therein. 100

17. In combination, a revolving crushing die having an annular crushing face disposed about an approximately vertical axis, a crushing roll having a peripheral crushing face acting toward said face to crush material between said faces, means for revolving one of said parts, means for supplying material to be crushed to said parts, means above said die affording a chamber communicating with said annular face and having an upper current outlet, means communicating inwardly below said die and affording a lower current inlet within said die, means concentric of said die comprising a casing surrounding and in spaced relation to said parts and comprising and enclosing a dust 115

collecting chamber around said parts and in communication with said upper outlet and said lower inlet and affording with them an endless passage through and under and 5 around said die, and means for causing a current to flow upwardly through said die to float fine material therefrom, and through said upper outlet and said dust collecting chamber and to return through said lower 10 inlet.

18. In combination, a revolving crushing die having an annular crushing face disposed about an approximately vertical axis, a crushing roll having a peripheral crushing face acting toward said face to crush material between said faces, means for revolving one of said parts, means for supplying material to be crushed to said parts, means affording a discharge chamber communicating 15 above and communicating with said annular face and having an upper current outlet, inwardly extending means under and communicating below said die and affording a lower current inlet thereto, means comprising a 20 casing surrounding and enclosing in spaced relation to said parts affording a passage surrounding said parts and communicating between said upper current outlet and said lower current inlet affording an endless passage 25 through and around said die, cleaning means between said current outlet and said current inlet across and intersecting said passage affording a filter for cleaning fine material from current traversing said passage to intercept floating particles and conduct them below the zone of such current, and means for causing a current to flow up 30 through said die to float fine material therefrom, through said upper outlet and through 35 said passage and filter and to return through said lower inlet.

19. In combination, a revolving die having an annular crushing face disposed about an approximately vertical axis, a crushing roll 45 having a peripheral crushing face acting toward said face to crush material between said faces, means for revolving one of said parts, means for supplying material to be crushed to said parts, means affording a current chamber above and surrounding said annular 50 face and communicating upwardly therefrom and having an upper current outlet, inwardly extending means communicating below said die and affording a lower current inlet inwardly of said annular face, a casing surrounding and in spaced relation to said parts and enclosing a chamber affording an annular downward passage surrounding said parts and communicating with said upper 55 outlet and said lower inlet, comprising a dust collector and a dust outlet, a casing within said casing and surrounding said lower inlet, affording a current passage between said dust collector and said lower inlet, and dust intercepting means surround- 60

ing said lower inlet and across and intersecting said passage to intercept dust floating therein in advance to said lower inlet, and means within said first casing for causing a fluid current to flow up through said die to float fine material therefrom, and through said upper outlet and said dust collector and to return through said filter and inwardly under said die through said lower inlet. 70

20. In combination, a die revolving about an axis and having an annular crushing face, a crushing roll having a peripheral crushing face acting radially toward said face to crush material between said faces, means for supplying material to be crushed to said faces, and means for sustaining and revolving said die comprising a sustaining traction face disposed radially of and revolving about said axis and sustaining and in driving connection with said die, and an axially adjustable traction roller having an edge traction face engaging said traction face and sustaining it to tractionally drive it and revolving about an axis radially of said first axis. 75

21. In combination, a die revolving about an axis and having an annular crushing face, a crushing roll having a peripheral crushing face acting impactively radially toward said face to crush materials between said faces, means for supplying material to be crushed to said faces, and means for revolving said die comprising a positioning traction face disposed radially of said die and revolving about said axis and positioning and in driving connection with said die, and an axially adjustable positioning traction roller revolving about an axis radially of said axis and having an edge traction face in tractive engagement with and positioning said traction face for tractionally driving it. 90 95

22. In combination, a die revolving about a substantially vertical axis and having an inner annular crushing face, a crushing roll having a peripheral crushing face acting impactively outwardly toward said face to crush material between said faces, means for supplying material to be crushed to said faces, and horizontally adjustable weight sustaining tractive means for revolving said die vertically sustaining the weight of said die. 100 110

23. In combination, a radially movable die revolving about a substantially vertical axis and having an inner annular crushing face, a crushing roll having a peripheral crushing face acting outwardly radially toward said face to crush material between said faces, means for feeding material to be crushed to said faces, and means for revolving said die movably connected radially of and to said die to permit radial movement of said die relatively to said revolving means. 120 125

24. In combination, a crushing die having an annular crushing face, a rotatable crushing roll having a peripheral crushing 130

face acting toward said face to crush material between said faces, means for supplying material to be crushed to said faces, and means for rotating said roll comprising a side traction face revolving about an axis, and an axially adjustable roller revolving about an axis radially of said first axis and having an edge traction face tractionally engaging said side face for revolving it.

10 25. In combination, a crushing die having an annular crushing face, a rotatable and revolute crushing roll having a peripheral crushing face acting toward said face to crush material between said faces, means for feeding material to be crushed to said faces, means for carrying said roll revolving about an approximately vertical axis, and means for revolving said carrying means comprising a traction face in driving connection with said 15 carrying means, and a traction roller tractionally engaging said face for tractionally revolving it.

26. In combination, a revolving die having an annular crushing face, a rotatable and 25 revolute crushing roll having a peripheral crushing face acting toward said face to crush material between said faces, means for supplying material to be crushed to said faces, rotating means for carrying said roll, and 30 variable speed means for revolving said die.

27. In combination, a revolving die having an annular crushing face, a rotatable and revolute crushing roll having a peripheral crushing face acting toward said face to crush 35 material between said faces, means for supplying material to be crushed to said faces, rotating means for carrying said roll, and variable speed means for revolving said rotating means.

40 28. In combination, a revolving die having an annular crushing face, a rotatable and revolute crushing roll having a peripheral crushing face acting toward said face to crush material between said faces, means for 45 supplying material to be crushed to said faces, rotating means for carrying said roll, and variable speed means for revolving said die and rotating means in reverse direction.

29. In combination, a revolving die having 50 an annular crushing face, a rotatable and revolute crushing roll having a peripheral crushing face acting toward said face to crush material between said faces, means for supplying material to be crushed to said faces, 55 rotating means for carrying said roll, and means for separately revolving said die and carrying means comprising tractional faces connected to each respectively and a traction roller tractionally engaging said faces 60 respectively.

30. In combination, a die revolving about an approximately vertical axis and having an annular crushing face, a rotatable and revolute crushing roll having a peripheral 65 crushing face acting toward said face to

crush material between said faces, means for supplying material to be crushed to said faces, means carrying said roll and rotating about said axis, tractional faces for revolving said die and carrying means respectively, and tractional rollers engaging said traction faces respectively for tractionally revolving and sustaining the weight of said die and said carrying means.

31. In combination, a die having an annular crushing face, a roll having a peripheral crushing face acting toward said face to crush material between said faces, means for supplying material to be crushed to said faces, and means for revolving one of said parts comprising reversely revolving members each having a side traction face opposite and spaced from that of the other, and a revolving member between said members and having an edge traction face engaging and tractionally driving said side traction faces.

32. In combination, a die having an annular crushing face, a roll having a peripheral crushing face acting toward said face to crush material between said faces, means for supplying material to be crushed to said faces and means for revolving one of said parts comprising oppositely revolving parts each having a side traction face opposite and spaced from that of the other, and a plurality of revolving parts between said revolving parts and each having an edge traction face opposite and engaging said side traction faces respectively for tractionally transmitting motion from one to another thereof.

33. In combination, a die having an annular crushing face, a roll having a peripheral crushing face acting toward said face to crush material between said faces, means for supplying material to be crushed to said faces, and means for revolving one of said parts comprising a member revolving about an axis and having a side traction face and members spaced about said axis and revolving about axes angular thereto each having an edge traction face tractionally engaging said side face for transmitting motion from one to another of said members.

34. In combination, a die having an annular crushing face, a roll having a peripheral crushing face acting with a radial outward stress toward said face to crush material between said faces, means for supplying material to be crushed to said faces, and means for revolving one of said parts comprising a member revolving about an axis and having a side traction face disposed in a plane parallel with the direction of such stress, and an axially adjustable member revolving about an axis angular to said first axis and having an edge traction face tractionally engaging said side face for transmitting motion thereto.

35. In combination, a horizontal revolving

- die having an annular crushing face within it for centrifugally holding on such face material to be crushed, a roll having a peripheral crushing face acting toward said face to crush material between said faces, means for supplying material to be crushed to said annular face, and means controlled by the quantity of such material centrifugally held on said annular face for varying the supply of such material to said faces. 5 70
36. In combination, a die having an annular crushing face, a movable rotatable and revolving roll having a peripheral crushing face acting toward said face to crush material between said faces, means for supplying material to be crushed to said annular face, and means moved by and revolving with said roll for automatically varying the supply of such material controlled by the movement 10 of said roll toward said face. 75
37. In combination, means affording a crushing chamber having a current inlet and a current outlet, means for feeding material to be crushed to said chamber, means for causing a fluid current to traverse said chamber from said inlet to said outlet, and current pressure operated feed varying means within said chamber and controlled by the pressure of said current adjacent to said inlet and comprising a movable feed gate for varying the supply of such material to said chamber and a movable current pressure operated wall adjacent to said inlet and actuating said gate with variations in such pressure. 25 80
38. In combination, means affording a crushing chamber having a current inlet and a current outlet, means for supplying to said chamber material to be crushed, means for causing a fluid current to traverse said chamber from said inlet to and through said outlet, and current pressure operated supply varying means within said chamber and controlled by the pressure of said current adjacent to said outlet and comprising a movable 40 85 feed gate for varying the supply of such material to said chamber and a movable current pressure operated wall adjacent to said outlet and actuating said gate with variations in such pressure. 90
39. In combination, means affording a crushing chamber having current ingress and egress passages, means for supplying material to be crushed to said chamber, means for varying such supply, and movable current 45 95 pressure operated operating means for operating said varying means and comprising a movable pressure operated wall actuating said varying means and in communication at one side with the ingress side of said chamber and at another side with the egress side of said chamber and movable to adapt said operating means to difference in current conditions at the respective sides of said chamber. 100
40. In combination, a die having an annular crushing face, a centrifugal roll having 50 105
- a peripheral crushing face acting toward said face to crush material between said faces, means for revolving said roll, means for supplying material to be crushed to said faces, and means for stopping such supply actuated by abnormal outward movement of said roll. 110
41. In combination, a horizontal revolving die having an inner crushing face for centrifugally holding on such face material to be crushed, a swinging roll within said die and having a peripheral crushing face acting toward said face to crush material between said faces, means for revolving said die, means for supplying material to be crushed between said faces, and movable shut-off means for stopping such supply controlled by the position of said roll and acting to shut off such supply when said roll swings outwardly excessively. 115 120
42. In combination, a die having an inner crushing face, a movable roll within said die and having a peripheral crushing face acting toward said face to crush material between said faces, means for revolving said roll, means for supplying material to be crushed to said inner face, means for driving said revolving means, and means for disconnecting said drive means operated by excessive movement of said roll for disconnecting said driving means from driving connection with said revolving means to then stop revolution of said roll. 125 130
43. In combination, means affording a crushing chamber, crushing elements within said chamber, means for revolving said elements, means for supplying material to be crushed to said chamber, means for driving said revolving means, drive disconnecting means for disconnecting said driving means from said revolving means, shut-off means for shutting off such supply, and operating means for operating said shut-off means comprising a connection between said shut-off means and said drive disconnecting means operating with said disconnecting means to shut-off such supply when said driving means are disconnected. 135
44. In combination, a casing enclosing a chamber, a receptacle mounted within and in spaced relation to said casing and having upper and lower openings communicating with said chamber, crushing elements for supplying pulverulent material within said receptacle, a revolving fan within said casing for causing a fluid current to flow therein through and around said receptacle, annular revolving means comprising a revolving wall spaced from and below the under side of and separate from said fan, and means for revolving said wall. 140 145
45. In combination, a casing enclosing an outer chamber, a revolving receptacle within and in spaced relation to said casing and enclosing an inner chamber and having upper 150

and lower openings communicating with said chamber, crushing elements for supplying pulverulent material within said receptacle and disposed above said lower opening, 5 means for revolving said receptacle, and means for causing a fluid current to flow up inwardly of said crushing elements and up through and around said receptacle to float fine material therefrom into said outer chamber and to return through said lower opening.

46. In combination, a casing enclosing an outer chamber, a revolving receptacle within and in spaced relation to said casing and enclosing an inner chamber and having upper 15 and lower openings communicating with said chamber, means for revolving said receptacle crushing elements for supplying pulverulent material within said receptacle and disposed above said lower opening, a lower receptacle 20 within said casing having an open upper end affording communication between said outer chamber and said lower opening, and means for causing a fluid current to circulate up inwardly of said crushing elements and up 25 through said revolving receptacle into said chamber and return around and outwardly of said revolving receptacle and said elements and between said receptacles to said lower opening.

47. In combination a casing enclosing an outer chamber, a revolving receptacle within and in spaced relation to said casing and enclosing an inner chamber and having upper and lower openings communicating with said 35 chamber, a lower receptacle within said casing having an open upper part spaced from said receptacle and affording communication between said outer chamber and said lower opening, crushing elements for supplying pulverulent material within said revolving receptacle and disposed above said lower opening, means for causing a fluid current to flow up inwardly of said crushing elements and up through said revolving receptacle and into 40 said outer chamber and return around and outwardly of said revolving receptacle and said elements and between said receptacles to said lower opening and filtering means in the path of such current for intercepting material floating therein toward said lower opening.

48. In combination, a horizontal die having a substantially vertical inner crushing face, a roll revolving about a substantially 55 vertical axis and within said die and having a substantially vertical peripheral crushing face acting horizontally toward said inner face for crushing material between said faces, means for revolving said roll about a substantially vertical axis, means for supplying within said die material to be crushed in said die, annular outwardly and upwardly inclined conical revolving impelling refeeding means below said roll and below and 60 inwardly of and having an outer edge in the

plane of the lower edge of the inner crushing face of said die for receiving such material falling through said die and revolving and centrifugally impelling such material outwardly and upwardly on to the inner crushing 70 face of said die and annular outwardly and downwardly inclined conical revolving refeeding means above said die and having a lower edge adjacent to and in the plane of the upper inner edge of said inner crushing face for receiving material rising from said die and refeeding such material downwardly 75 on to the inner face of said die.

49. In combination, a die revolving about a substantially vertical axis and having a substantially vertical inner crushing face, a roll rotatable about a substantially vertical axis and within said die and having a substantially vertical peripheral crushing face acting horizontally toward such inner face 80 for crushing material between said faces, means for revolving said die, means for supplying within said die material to be crushed in said die, annular outwardly and upwardly inclined conical revolving impelling refeeding means below said roll and below and inwardly of and having an outer edge in the plane of the lower edge of the inner crushing 85 face of said die for receiving such material falling through said die and revolving and centrifugally impelling such material outwardly and upwardly on to the inner crushing face of said die and annular revolving downward refeeding means above said die and having a lower edge adjacent to and in the plane of the upper inner edge of said inner crushing face for receiving material rising from said die and refeeding such material downwardly 90 on to the inner face of said die.

50. In combination, a horizontal die having a substantially vertical crushing face, a rotatable and revoluble roll for revolving about a substantially vertical axis within said die and having a substantially vertical peripheral crushing face acting horizontally toward said inner face for crushing material between said faces, means for revolving said roll, means for supplying within said die material to be crushed in said die, refeeding means below the inner crushing face of said die for receiving such material falling through said die and refeeding such material outwardly and upwardly on to the inner crushing face of said die, and annular 100 revolving downward refeeding means above said die and having a lower edge adjacent to and in the plane of the upper inner edge of said inner crushing face for receiving material rising from said die and refeeding such material downwardly 105 on to the inner face of said die.

51. In combination, a revolving and radially movable horizontal die having a substantially vertical inner crushing face, a 110

crushing roll rotating about a substantially vertical axis and within said die and having a substantially vertical peripheral crushing face acting radially toward and exerting a 5 crushing stress horizontally toward said inner face for crushing material between said faces, means for supplying material to be crushed in said die, and means drivingly connected to said die and as to which said die is radially 10 movable for revolving said die about a substantially vertical axis.

52. In combination, a revolving and radially movable horizontal die having a substantially vertical inner crushing face, a rotatable crushing roll rotating about a substantially vertical axis and within said die and having a substantially vertical peripheral crushing face acting radially toward and exerting a crushing stress horizontally toward 15 said inner face for crushing material between said faces, means for supplying material to be crushed in said die, means as to which said die is radially movable drivingly connected to said die for revolving it, and positioning means movably positioning said die radially relatively to said driving means.

53. In combination, a revolving horizontal die having a substantially vertical inner crushing face, a crushing roll rotating about 20 a substantially vertical axis and within said die and having a substantially vertical peripheral crushing face acting radially toward and exerting a crushing stress horizontally outwardly toward said inner face for crushing material between said faces, means for supplying material to be crushed in said die, driving means drivingly connected to said die for revolving said die about a substantially vertical axis, and yielding means 25 positioning in the direction of said stress for yielding in the direction of said stress for positioning said die relative to said driving means.

54. In combination, a die revolving about a substantially vertical axis and having an 30 annular crushing face, a rotatable roll having a peripheral crushing face acting toward said face to crush material between said faces, means for revolving said die, means for supplying material to be crushed to said faces, means for causing a fluid current to flow up 35 through, out over, down without, and return in under, said revolving die, to float fine material from said die, and means affording a revolving die encircling endless current passage extending up through, out over, down without, and in under, said revolving die, for conducting such current up through, out over, and down without, said revolving die, and for returning such current in under said revolving die.

55. In combination, means affording a revolving crushing chamber, crushing elements in said chamber, means for revolving said chamber, means for supplying material to be crushed to said elements, means for causing 40

a fluid current to flow in, through, out of, and down without, said revolving chamber, and to return under said revolving chamber, to float fine material from said chamber, and means affording a revolving crushing chamber encircling endless current passage extending into and through, and out of, and down without, and under, said revolving chamber, for conducting such current into and through and down without, said revolving chamber, and for returning such current under said revolving chamber.

56. In combination, a die revolving about a substantially vertical axis and having an annular crushing face, a rotatable roll having a peripheral crushing face acting toward said face to crush material between said faces, means for revolving said die, means for supplying material to be crushed to said faces, means for causing a fluid current to flow in an endless path up through, out over, down without, and in under, said revolving die to float fine material from said die, material intercepting means across said path for intercepting and conducting out of the zone of such current fine material floating in such current and means affording a revolving die encircling endless current passage extending up through, out over, down without, and in under said revolving die, for conducting such current up through, out over, and down without, said revolving die and through said intercepting means, and for returning such current in under said revolving die.

57. In combination, an outer casing enclosing an outer chamber and having a downwardly inclined deflecting wall around the upper part of said chamber, means affording a crushing chamber within and in spaced relation to said outer casing and having a lower current inlet and an upper current outlet communicating with said outer chamber, crushing elements within said inner chamber, means for operating one of said elements, means for supplying material to be crushed to said elements, means affording an endless current passage extending up through, out over, down without, and returning in under said crushing chamber, and means for causing a fluid current to circulate through said passage to float fine material from said crushing chamber comprising revolving fan blades between said chambers and within and opposite and encircled by said inclined deflecting wall for directing such current toward said wall to accelerate circulation of such current through said passage.

58. In combination, an outer casting enclosing an outer chamber and having a downwardly inclined deflecting wall above said chamber, a crushing die within and in spaced relation to said casting and having an annular crushing face disposed about a vertical axis and having a lower current inlet and an upper current outlet communicating with

said outer casing, means affording an endless current passage up through, out over, down around, and in under, said die, a rotatable crushing roll having a peripheral crushing 5 face acting toward said face to crush material between said faces, means for rotating said roll, means for supplying material to be crushed between said faces, and means for causing a fluid current to flow up through, 10 out over, down without, and return in under, said die to float fine material from said die, comprising revolving fan blades above said die and opposite and encircled by said deflecting wall for directing such current to 15 ward said deflecting wall to accelerate its circulation through said passage and having inclined outer edges substantially coinciding with the inclination of said deflecting wall and co-operating with the latter for circulat- 20 ing such current.

59. In combination, a casing enclosing an outer chamber and having a downwardly inclined deflecting wall above and surrounding said chamber, means within and in spaced 25 relation to said casing affording a crushing chamber having a lower current inlet and an upper current outlet communicating with said outer chamber, crushing elements in said crushing chamber, means for operating one 30 of said elements, means for supplying material to be crushed to said elements, and means for causing a fluid current to flow up through, out over, down without, and return in under, said crushing chamber, to float fine material 35 from the latter, comprising radially adjustable revolving fan blades within and opposite and encircled by said deflecting wall for directing such current towards said deflecting wall to accelerate such circulation of such 40 current, and adjustable relatively to said deflecting wall to vary such current.

60. In combination, a horizontally movable outer crushing member having an inner crushing face, a movable inner crushing 45 member having an outer crushing face within said outer member and acting outwardly toward said inner face to crush material between said faces, means for causing said inner member to exert an outward crushing 50 stress toward said inner face, an outer casing around and spaced from said outer member, and within which said outer member is horizontally movable, for movably enclosing said outer member, and a horizontally 55 movable sustainer for said outer member, within and movable horizontally relatively to said outer casing, for vertically sustaining said outer member and permitting it to move horizontally within said casing in the direction 60 of said stress.

61. In combination, a horizontally movable outer crushing member having an inner crushing face, a movable inner crushing element within said outer member and having opposed outwardly acting crushing faces with 65

in and exerting opposed outward crushing stresses toward said inner face to crush material between said inner and outer faces, means for operating said inner element, means for supplying material to be crushed by said faces, an outer casing around and spaced from said outer member, and as to which said outer member is horizontally movable, for movably enclosing said outer member, and an outer member sustainer on which 70 said outer member is movably mounted and spaced from said outer casing, and as to which said outer member is horizontally movable, for vertically positioning said outer member and permitting its movement horizontally within said casing in the directions of said opposed stresses.

62. In combination, a horizontally movable outer crushing member having an inner annular crushing face, a movable inner crushing member having an outer annular crushing face within and exerting an outward crushing stress toward said inner face, to crush material between said faces, means for moving said inner member, means for supplying material to be crushed by said faces, an outer casing around and spaced from said outer member, and as to which said outer member is horizontally movable, for movably enclosing said outer member, and a horizontally 85 movable sustainer connection between said outer casing and said outer member, and within and movably connected to said outer casing, and by which said outer member is vertically sustained in spaced relation to said outer casing, and spaced within and horizontally movable as to said outer casing, for 90 vertically supporting said outer member and permitting its horizontal movement within said outer casing in the direction of such 95 stress.

63. In combination, a radially movable outer horizontal crushing member having an inner annular crushing face, a rotary inner crushing member having a peripheral crushing face within and acting radially outwardly toward said inner face for crushing material between said faces, means for supplying material to be crushed by said faces, means for rotating said inner member, an annular outer casing around and spaced from said outer member, and as to which said outer member is radially movable, for movably enclosing said outer member, and a radially 110 movable outer member sustainer for said outer member, within and spaced from and radially movable relatively to said outer casing, for vertically sustaining said outer member and permitting its radial movement within said casing in the direction of such stress.

64. In combination, a radially movable revoluble horizontal die having an internal annular crushing face disposed about a substantially vertical axis, a rotatable crushing roll rotatable about a substantially vertical 115

axis and within and eccentric of said die and having a peripheral crushing face acting toward and exerting a crushing stress horizontally outwardly toward said inner face for crushing material between said faces, 5 means for supplying material to be crushed in said die, means for rotating said roll, and a sustainer by which said radially movable revolute die is vertically sustained, as to 10 which said die is radially movable and revolute, for revolubly supporting said die and for permitting radial movement of said die in the direction of said stress.

65. In combination, a horizontally movable 15 revolute die having an annular internal crushing face disposed about a substantially vertical axis a rotatable crushing roll rotatable about a substantially vertical axis within and eccentric of said die and having a 20 peripheral crushing face acting toward and exerting a crushing stress horizontally outwardly toward said inner face for crushing material between said faces, means for supplying material to be crushed to said faces, 25 means for rotating said roll, and a horizontally movable sustainer for said horizontally movable revolute die, by which said die is vertically and horizontally movably sustained, for vertically supporting said die 30 relatively to said roll and permitting horizontal movement of said die in the direction of said stress.

66. In combination, a radially movable 35 revolute die having an annular internal crushing face disposed about a substantially vertical axis, a rotatable crushing roll rotatable about a substantially vertical axis within and eccentric of said die and having a 40 peripheral crushing face acting toward and exerting a crushing stress horizontally outwardly toward said inner face for crushing material between said faces, means for supplying material to be crushed by said faces, 45 means for rotating said roll, and a revolute sustainer by which said radially movable revolute die is vertically sustained, and as to 50 which said die is radially movable, for revolubly supporting said die and for permitting radial movement of said die in the direction of said stress.

67. In combination, a radially movable 55 revolute die having an annular internal crushing face disposed about an approximately vertical axis, a rotatable crushing roll 60 rotatable about a substantially vertical axis within and eccentric of said die and having a peripheral crushing face acting radially toward and exerting a crushing stress horizontally outwardly toward said inner face for crushing material between said faces, 65 means for supplying material to be crushed by said faces, means for rotating said roll, and a revolute and radially movable sustainer by which said die is vertically supported, for vertically supporting said die

and permitting radial movement of said die in the direction of said stress.

68. In combination, a horizontal and mov- 70 able die having an annular internal crushing

face disposed about a substantially vertical axis, a rotatable crushing roll rotatable about a substantially vertical axis within and eccentric of said die and having a peripheral

crushing face acting radially toward and exerting a crushing stress horizontally out- 75

wardly toward said inner face for crushing material between said faces, means for sup- 80

plying material to be crushed by said faces, means for rotating said roll, a casing around 85

and spaced from said die, and affording an endless current passage extending up through, out over, down around, and return- 90

ing in under, said movable die, and within which said die is movable, blower means for causing a fluid current to 95

circulate through said passage and flow up through and down around, and to return in under, said die, to float fine material from said die, baffle means within 100

said casing and across said passage, and con- 105

centric of said die and as to which said die is movable, for intercepting and conducting out of the zone of such current fine material float- 110

ing in such current, and die sustainer means concentric of said baffle means and by which 115

said die is vertically and movably sustained relatively to said baffle means, for vertically and movably sustaining said die relatively to said baffle means and to said outer casing.

69. In combination, a radially movable 120 horizontally disposed crushing die having an internal annular face disposed about a sub- 125

stantially vertical axis, a rotatable crushing roll rotatable about a substantially vertical axis within and eccentric of said die and hav- 130

ing a peripheral crushing face acting with an outward crushing stress toward said inner face to crush material between said faces, 135

means for supplying material to be crushed by said faces, means for rotating said roll, 140

means affording an endless current passage extending up through, out over, down around, and return in under said movable die, means for causing a fluid current to circu- 145

late through said passage and flow up through and down around and return in 150

under said die to float fine material from said die, fine material intercepting means across 155

said endless passage, and as to which said die is radially movable, for intercepting and 160

conducting out of the zone of such current fine material floating in such returning current, and a radial movement joint between 165

said radially movable die and said intercepting means, for permitting radial movement of said die relative to said intercepting 170

means.

70. In combination, means affording a re- 175

volving crushing chamber, crushing elements in said chamber, means for revolving said

chamber, means for supplying material to be crushed to said elements, means affording a revolving crushing chamber encircling endless current passage extending into and through, out over, and down without, said revolving chamber and returning under said crushing elements, means for causing a fluid current to circulate through said endless passage and flow up through said revolving chamber and return in under said crushing elements for separating and floating fine material from said chamber, material intercepting means across said endless passage for intercepting and conducting out of the zone of such current fine material floating in such current, and means affording revolution permitting means between said revolving chamber and said intercepting means for permitting revolution of said chamber relative to said intercepting means.

71. In combination, a revolving crushing die revolving about a substantially vertical axis and having an annular inner crushing face, a rotatable crushing roll rotatable about a substantially vertical axis within and eccentric of said die and having a peripheral crushing face acting toward said inner face to crush material between said faces, means for revolving said die, means for supplying material to be crushed by said faces, means affording a revolving die encircling endless current passage up through, out over, down without, and returning in under, said revolving die, means for causing a fluid current to circulate through said endless passage and flow up through and out over said revolving die and return in under said revolving die, for separating and floating fine material from said die, material intercepting means across said endless passage, and as to which said die is revolvable for intercepting and conducting out of the zone of such current fine material floating in such current, and a revoluble joint between said revolving die and said intercepting means for permitting revolution of said die relatively to said intercepting means.

72. In combination, in a pulverizer, means affording a revolving crushing chamber having an upper current outlet and a lower current inlet, crushing elements in said chamber, means for revolving said chamber, means for supplying material to be crushed by said elements, means affording an endless current passage communicating up through, out over, down around, and returning in under, said revolving chamber, and revolving fan blades above and concentric of said revolving chamber for causing a separating fluid current to circulate through said endless passage and flow up through and out over said revolving chamber to separate and out-float fine material from said revolving chamber and to return such current under said revolving chamber.

73. In combination, in a pulverizer, a revolving crushing die having an annular crushing face disposed about an approximately vertical axis, and affording a current outlet above said face and a current inlet below said face, a rotatable crushing roll having a peripheral crushing face acting toward said face to crush material between said faces, means for revolving said die, means for supplying material to be crushed by said faces, means affording a die encircling endless current passage communicating up through, out over, down around, and returning in under, said die, and revolving fan blades above and concentric of said die for causing a separating fluid current to circulate through said endless passage and flow up through and out over said revolving die to separate and out-float fine material from said revolving die and to return such current below said revolving die.

74. In combination, in a pulverizer, means affording a pulverizing chamber having an upper current outlet and a lower current inlet, pulverizing elements in said chamber, means for operating said elements, means for supplying material to be crushed by said elements, means affording an endless current passage communicating up through, out over, down around, and returning in under, said chamber, fine material intercepting means without said chamber and across said passage for intercepting and conducting across said passage fine material floating in said passage, and revolving fan blades above said intercepting means and revolving in said passage, for causing a separating fluid current to circulate through said endless passage and flow up through and out over said chamber to separate and float fine material from said chamber to said intercepting means and return cleaned fluid through said intercepting means and below said chamber.

75. In combination, in a pulverizer, a crushing die having an annular crushing face disposed about an approximately vertical axis, and affording above said face a current outlet and below said face a current inlet, a rotatable crushing roll having a peripheral crushing face acting toward said face to crush material between said faces, means for rotating said roll, means for supplying material to be crushed by said faces, means affording a die encircling endless current passage communicating up through, out over, down around, and returning in under, said die, fine material intercepting means across said passage and without said die, for intercepting and conducting out of said passage fine material floating in said passage, and revolving fan blades above said intercepting means and concentric of said die, for causing a separating fluid current to circulate through said passage and flow up through said die, to separate and float fine material

from said die toward said intercepting means and to return cleaned current through said intercepting means and below said die.

76. In combination, in a pulverizer, means
 5 affording a crushing chamber having an upper current outlet and a lower current inlet, crushing elements in said chamber, means for operating said elements, means for supplying material to be crushed by said elements, means affording an endless current passage communicating up through, out over, down around, and returning in under, said chamber, non-rotary fine material intercepting means across said passage, and intermediate said outlet and said inlet, for intercepting and conducting across said passage fine material floating in said passage, and revolving fan blades above and concentric of said intercepting means, for causing a separating 75
 10 fluid current to circulate through said endless passage and flow up through and out over said chamber to separate and float fine material from said chamber toward said intercepting means, and to return cleaned current 80
 15 through said intercepting means to said lower inlet.

77. In combination, in a pulverizer, means affording a revolving crushing chamber having an upper current outlet and a lower current inlet, crushing elements in said chamber, means for revolving said chamber, means for supplying material to be crushed by said elements, means affording an endless current passage communicating up through, out over, 85
 20 down around, and returning in under, said revolving chamber, means for causing a separating fluid current to circulate through said passage and flow up through and out over said revolving chamber to separate and 90
 25 out-float fine material from said revolving chamber, and adjustable current intensity varying means above said revolving chamber, for varying the intensity of such separating current for varying the fineness of such 95
 30 separation.

78. In combination, in a pulverizer, means affording a crushing chamber, having an upper current outlet and a lower current inlet, crushing elements in said chamber, means 100
 35 for operating said elements, means for supplying material to be crushed by said elements, means affording an endless current passage communicating up through, out over, down around, and returning in under, said 105
 40 chamber, means for causing a separating fluid current to circulate through said passage and flow up through and out over said chamber to separate and out-float fine material from said chamber, and current intensity 110
 45 varying means, for varying the intensity of such current, for varying the fineness of such separation, comprising variable speed revolving fan blades above said chamber, and means for revolving said blades at variable speed.

79. In combination, in a pulverizer, means affording a crushing chamber having an upper current outlet and a lower current inlet, crushing elements in said chamber, means for operating said elements, means for supplying material to be crushed by said elements, means affording an endless current passage communicating up through, out over, down around, and returning in under, said chamber, means for causing a separating 75
 50 fluid current to circulate through said passage and flow up through and out over said chamber to separate and out-float fine material from said chamber, and current intensity varying means, for varying the intensity of such current, for varying the fineness of such out-floated material, comprising 80
 55 adjustable revolving fan blades revolving in said endless passage and adjustable to vary the intensity of such current. 85

80. In combination, in a pulverizer, means affording a crushing chamber having an upper current outlet and a lower current inlet, crushing elements in said chamber, means for operating said elements, means for supplying material to be crushed by said elements, means affording an endless current passage communicating up through, out over, down around, and returning in under, said chamber, and means for causing a separating 90
 50 fluid current to circulate through said passage and flow up through and out over said chamber, to separate and out-float fine material from said chamber, comprising spaced revolving spokes above said outlet, 95
 55 affording between them upward passages for such current and above them a current outlet chamber, and up-standing revolving fan blades, having inner edges up-standing substantially their entire width above said 100
 60 spokes and encircling said outlet chamber. 105

In witness whereof, I have hereunto signed my name.

GEORGE HOLT FRASER.
